UNITED STATES PATENT OFFICE.

ELSTON A. ROOP, OF LOUISVILLE, KENTUCKY.

DESIGN FOR A GOLF TEE.

Application filed March 8, 1929. Serial No. 30,389. Term of patent 3½ years.

To all whom it may concern:

Be it known that I, ELSTON A. ROOP, a citizen of the United States, residing at Louisville, in the county of Jefferson and State of Kentucky, have invented a new, original, and ornamental Design for a Golf Tee, of which the following is a specification, reference being had to the accompanying drawing, forming part thereof.

The figure is a perspective view of a golf tee, showing my new design.

I claim:

The ornamental design for a golf tee, as shown.

ELSTON A. ROOP.
